N. PETERS, PHOTO-LITHOGRAPHER, WASHINGTON, D. C.

UNITED STATES PATENT OFFICE.

CHRISTOPHER AUMOCK, OF COLUMBUS, OHIO.

MACHINE FOR SCOURING KNIVES AND FORKS.

Specification of Letters Patent No. 8,646, dated January 13, 1852.

To all whom it may concern:

Be it known that I, CHRISTOPHER AUMOCK, of the city of Columbus, in the county of Franklin and State of Ohio, a citizen of the United States of America, have invented a new and useful improvement on scouring or polishing machine for scouring or polishing knives and forks or any other implements made of metallic substances; and I do hereby declare, that the following is a full, clear, and exact description of the construction and operation of said machine, reference being had, to the annexed drawings, which make a part of the specifications.

Figure 1 descriptive, and elevated view of said machine, with all the parts put together. Fig. 2, is a representation of the two cylinder brushes, which when in operation, do the work of scouring or polishing.

Letter A in Fig. 1 is the balance wheel; letter B is a handle attached to the balance wheel, for the purpose of operating the machine; letter C, is the shaft, on which the balance wheel hangs, said shaft resting on its journals, in bearings in the posts of said machine; letter D is a box in which the cylinder brushes are hung, and inclosed while said machine is in operation, which is set in the frame; letter E is cover of box; letter F is posts, and letter G is rails, which constitute the frame, of said machine.

Letter H Fig. 2 is cylinder brushes which lie in a horizontal position when hung in the box, and when the machine is in motion, revolve on their axis toward each other in such a manner that the bristles, or whatever substance the cylinder brushes are composed of mesh into each other say one eighth of

an inch, and at the same time, the lower surface is in a liquid polishing or souring substance, held by the box, composed of alcohol, or any other liquid that may be chosen, mixed with brickdust, emery or any other material used for scouring or polishing. 40 45

Letter I Fig. 1 is pulleys on the ends of the shafts that run through the cylinder brushes; letter K is belt running over balance wheel and pulleys operating the cylinder brushes; letter L is friction pulley attached to post for belt to work over; letter M is bearings, in which the journals of the cylinder brushes rest, which are so constructed, that the brushes may be made to revolve closer together, or further apart, at 50 55 the pleasure of the operator.

I claim—

The construction of this machine composed of two cylinder brushes with their peripheries in contact which causes the friction necessary for scouring or polishing, 60 and at the same time keeps the cylinder brushes which do the work of polishing or scouring wet with the polishing substance continually, while the machine is in motion, 65 by immersing the under side of said brushes, in the liquid, as they revolve around on their axis as above mentioned; the article to be scoured or polished, must be held in a perpendicular position, and moved up and down 70 between the cylinder brushes, while in the act of scouring or polishing.

Columbus, June 1, 1850.

CHRISTOPHER AUMOCK.
